BRAKE OPERATING MEANS

Filed May 11, 1925

INVENTOR
LUDGER E. LABRIE
BY Mr. W. McConkey
ATTORNEY

UNITED STATES PATENT OFFICE.

LUDGER E. LA BRIE, OF SOUTH BEND, INDIANA, ASSIGNOR TO BENDIX BRAKE COMPANY, OF CHICAGO, ILLINOIS, A CORPORATION OF ILLINOIS.

BRAKE-OPERATING MEANS.

Application filed May 11, 1925. Serial No. 29,369.

This invention relates to brakes, and is illustrated as embodied in an automobile chassis having a brake for a front or other swivelled wheel. An object of the invention is to provide an efficient but economical construction, by reducing the number of parts.

Having this object in view, the invention 10 contemplates the use of a lever arranged to apply the brake directly, instead of through a cam or the like, and which, in the case of an internal brake such as shown in the drawings, may engage the free ends of the shoes, or equivalent friction means, to pry them 15 apart into engagement with the drum.

An important feature of the invention relates to the use of such a brake on a front or other swivelled wheel, without necessitating additional complicated connections, by 20 so arranging the lever that, when the brake is applied, a part engaged by the brake-applying means is swung from an idle position spaced from the swivelling axis to an active position substantially in that axis, so that 25 the brake connections do not interfere with swivelling the wheels. In one desirable arrangement, the brake-applying means includes a second lever fulcrumed on the axle, or otherwise supported independently of the 30 wheel knuckle, and engaging the above-described part of the lever which spreads the brake shoes.

If it be desired to relieve the pressure on the outer brake, or otherwise vary the braking, in rounding a corner, the point of engagement between the two levers or their equivalents is, in active position, not exactly in the mathematical axis about which the wheel swivels, but slightly at one side. If 40 the two rigid levers are used, the point of engagement is slightly outside the swivelling axis in order to relieve the pressure on the outer brake on a turn.

Other objects and features of the invention, including a novel mounting for the lever, and an arrangement permitting the use 45 of interchangeable brake shoes, will be apparent from the following description of one illustrative embodiment shown in the accompanying drawings, in which:

Figure 1 is a vertical section just inside the wheel, showing the brake shoes in side elevation;

Figure 2 is a vertical section at right angles to Figure 1, through the brake, and

showing the swivelling of the knuckle to the axle;

Figure 3 is a detail section on the line 3-3 of Figure 1, showing the means for positioning the free end of the shoe laterally; and

Figure 4 is a diagram illustrating the release of the outer wheel on the turn.

In the arrangement illustrated, the chassis includes a drum 10 rotatably mounted with its wheel on a knuckle 12 swivelled, by the usual king pin, at one end of an axle 14. The friction device carried by the knuckle is shown as an internal expanding set of shoes, including a reverse shoe 16 anchored at 18 65 on a backing plate 20, and a forward shoe 22 anchored at 24 and operated by circumferential movement of a servo shoe 26 against the resistance of a spring 28. Shoes 22 and 26 are pivotally connected at 30. Anchor 70 70 passes through a relatively large opening in the web of shoe 22, and anchor 24 passes through similar large openings in arms forming a forked end of shoe 16 straddling the anchored end of shoe 22. A spring 32 urges 75 shoes 16 and 26 away from the drum.

Each of the shoes 26 and 16, adjacent its free end, is formed with a slot 34, through which passes a stud 36 carried by the backing plate 20. Each stud 36 serves to center 85 a spring 38, confined between the backing plate 20 and a washer engaging the shoe, and a spring 40, confined between a washer 42 held by a cotter pin 44 and a washer 90 engaging the shoe. The springs serve to 95 position the free ends of the shoes laterally.

A lever 46 is arranged to engage the free ends of the shoes or their equivalent, and is shown as pivoted at 48 between flanges 50 on the end of shoe 26, and as having a point of engagement between its ends with a wear plate 52 secured to the end of shoe 16. In order that shoes 16 and 26 may be identical and interchangeable, shoe 16 is also formed with flanges 50. Thus rocking the lower 100 end of lever 46 to the right (Figure 1) will cause it to pry the shoes apart to force them against the drum.

According to an important feature of the invention, the lever 46 has a part, such as 105 its lower end, which is engaged by the brake-operating means, and which is movable in applying the brake from an idle position spaced from the swivelling axis, to an active position substantially in that axis, so that 110

the brake does not interfere with swivelling the wheel in steering.

I prefer to operate the brake by means including a lever 54, supported on axle 14 or otherwise independent of the knuckle, and which engages the above-described part of lever 46. The lever 54 is shown with a ball end, and lever 46 as having a flat surface engaged thereby, but any other suitable connection may be used.

When it is desired to vary the braking on a turn, the point of engagement of levers 54 and 46, or their equivalents, is not exactly in the mathematical axis of swivelling, even when the brake is applied,—i. e., in active position,—but is slightly at one side of that axis. The diagram in Figure 4 illustrates the arrangement when the pressure on the outer brake is to be relieved on a turn.

In this diagram, W is a line through the swivelling axis (i.e., the king pin axis) K parallel to the wheel, WR is a corresponding line in rounding a corner to the right, and WL is a corresponding line in rounding a corner to the left. L indicates the lever 54 in its active position, and C indicates its point of engagement with lever 46.

Now it will be evident that, when the wheel is swivelled from a position parallel to line W to a position parallel to line WR, point C tends to move to CR,—that is, away from lever L, to relieve the pressure on the brake, which is on the outside of the turn. When the wheel is swivelled to a position parallel to WL, point C (arm 46) tends to move to CL,—that is, it crowds against lever L and tightens its brake, which is then on the inside of the turn. Of course, the connections operating levers 54 on opposite sides should be unequalized when this effect is desired.

While one illustrative embodiment has been described in detail, it is not my intention to limit the scope of the invention to that particular embodiment, or otherwise than by the terms of the appended claims.

I claim:

1. Operating means for a brake device mounted on a swivelled knuckle rotatably supporting a drum, and comprising, in combination with said parts, a lever directly connected to said device and movable from an idle position in which a part is spaced from the swivelling axis to an active position in which the device is frictionally engaged with the drum and in which said part is adjacent the swivelling axis, and means engaging said part of the lever to move the lever from idle to active position.

2. Operating means for brake shoes mounted on a swivelled knuckle rotatably supporting a drum, and comprising, in combination with said parts, a lever directly engaging the free ends of said shoes and

movable from an idle position in which a part is spaced from the swivelling axis to an active position in which the shoes are frictionally engaged with the drum and in which said part is adjacent the swivelling axis, and means engaging said part of the lever to move the lever from idle to active position.

3. Operating means for an expansible friction device mounted on a swivelled knuckle rotatably supporting a drum, and comprising, in combination with said parts, a lever engaging the free ends of said device and movable from an idle to an active position to spread said device against the inside of the drum, the lever having a part moving from an idle position spaced from the swivelling axis to an active position adjacent said axis, and means engaging said part of the lever to rock it to operate the friction device.

4. Operating means for an expansible friction device mounted on a swivelled knuckle rotatably supporting a drum, and comprising, in combination with said parts, a lever pivoted to one free end of said device and engaging the other free end and movable about its pivoted end as a fulcrum to spread said device against the inside of the drum, the lever having a part moving from an idle position spaced from the swivelling axis to an active position adjacent said axis, and means engaging said part of the lever to rock it about its pivoted end to operate the friction device.

5. Operating means for spreading apart the adjacent free ends of a plurality of friction shoes arranged within a drum rotatably mounted on a swivelled knuckle, and comprising, in combination with said parts, a lever pivoted to the free end of one shoe and engaging the free end of the other shoe, and having its free end movable from a position spaced from the swivelling axis to a position adjacent said axis, and means engaging said free end to rock the lever to apply the brake.

6. Operating means for spreading apart the adjacent free ends of a plurality of friction shoes arranged within a drum rotatably mounted on a swivelled knuckle, and comprising, in combination with said parts, a lever pivoted to the free end of one shoe and engaging the free end of the other shoe, and having its free end movable from a position spaced from the swivelling axis to a position adjacent said axis, and a second lever supported independently of the knuckle and engaging said free end to rock the first lever to apply the brake.

7. Operating means for spreading apart the adjacent free ends of a plurality of friction shoes arranged within a drum rotatably mounted on a knuckle swivelled on an axle, and comprising, in combi-

nation with said parts, a lever pivoted to the free end of one shoe and engaging the free end of the other shoe, and having its free end movable from a position spaced 5 from the swivelling axis to a position adjacent said axis, and a lever pivoted on the axle and engaging said free end to rock the first lever to apply the brake.

8. Operating means for an expansible and 10 contractable friction device engageable with a drum rotatably mounted on a swivelled knuckle, and comprising, in combination with said parts, a lever engaging the adjacent free ends of said device and movable about 15 its fulcrum to engage said device with the drum, the lever having one end movable from an idle position spaced from the swivelling axis to an active position adjacent that axis, and a second lever supported independently of the knuckle and engaging said 20 end of the first lever to rock the first lever about its fulcrum to apply the brake.

9. A brake comprising, in combination, a drum, a plurality of shoes within the drum 25 having adjacent free ends, and a lever pivoted to the free end of one shoe and engaging the adjacent free end of the opposite shoe to spread the shoes against the drum, the two shoes both being formed for pivotal 30 mounting of the lever, and being in all other respects identical and interchangeable.

10. A brake comprising, in combination, a drum, friction means within the drum having adjacent ends of considerable depth 35 radially of the drum, and an operating lever extending radially of the drum between said ends and pivoted at its extreme outer end to the outer portion of one of said ends and thence bent to clear the inner portion of said 40 one end and engage the inner portion of the other of said ends and thence continued to form an operating portion between the friction means and the center of the drum.

11. A vehicle having, in combination, a 45 pair of swivelled knuckles, each supporting an expansible and contractable friction device engageable with a rotatably mounted drum, a lever engaging the free ends of each friction device and operable to engage said 50 device with its drum by movement from an idle position in which a part is spaced from the swivelling axis of its knuckle to an active position slightly at one side of said axis, and unequalized means engaging said parts of 55 the levers to operate the brakes, the active positions of the points of engagement between said levers and means being so positioned with respect to the swivelling axes that the braking is varied on a turn.

12. A vehicle having, in combination, a 60 pair of swivelled knuckles, each supporting an expansible and contractable friction device engageable with a rotatably mounted drum, a lever engaging the free ends of each friction device and operable to engage said device with its drum by movement from an 65 idle position in which a part is spaced from the swivelling axis of its knuckle to an active position slightly at one side of said axis, and unequalized means engaging said parts of 70 the levers to operate the brakes, the active positions of the points of engagement between said levers and means being so positioned with respect to the swivelling axes that the pressure on the outer brake is lessened on a turn. 75

13. A vehicle having, in combination, a pair of swivelled knuckles, each supporting an expansible and contractable friction device having adjacent free ends and engageable with a rotatably mounted drum, a lever 80 engaging the free ends of each friction device and operable to engage said device with its drum by movement from an idle position in which a part is spaced from the swivelling axis of its knuckle to an active position in which said part is spaced slightly at one side of said axis, and unequalized brake-operating means including levers supported independently of the knuckles and engaging said 85 parts of the first levers to operate them, the points of engagement between the levers in active positions being so positioned with respect to the swivelling axes as to cause variation in the braking when the knuckles are 90 swivelled.

14. A vehicle having, in combination, a pair of swivelled knuckles, each supporting an expansible and contractable friction device having adjacent free ends and engageable with a rotatably mounted drum, a lever 100 engaging the free ends of each friction device and operable to engage said device with its drum by movement from an idle position in which a part is spaced from the swivelling 105 axis of its knuckle to an active position in which said part is spaced slightly at one side of said axis, and unequalized brake-operating means including levers supported independently of the knuckles and engaging said 110 parts of the first levers to operate them, the points of engagement between the levers in active position being on the outside of their respective swivelling axes.

In testimony whereof I have hereunto 115 signed my name.

LUDGER E. LA BRIE.
